UNITED STATES PATENT OFFICE.

JULIUS C. LOWRY, OF DETROIT, MICHIGAN.

DESIGN FOR A BACKPLATE FOR LIGHTING FIXTURES.

Application filed May 15, 1926. Serial No. 17,729. Term of patent 7 years.

To all whom it may concern:

Be it known that I, JULIUS C. LOWRY, a citizen of the United States, residing at Detroit, in the county of Wayne and State of Michigan, have invented a new, original, and ornamental Design for a Backplate for Lighting Fixtures, of which the following is a specification, reference being had to the ac-

companying drawing, forming part thereof.

The figure is an elevation of a backplate for lighting fixtures embodying my new design.

I claim:

The ornamental design for a backplate for lighting fixtures, as shown.

JULIUS C. LOWRY.
